UNITED STATES PATENT OFFICE.

THEODORE A. MOOLTEN, OF NEW YORK, N. Y.

DESIGN FOR A SPAT.

55,394.

Specification for Design.

Patented June 1, 1920.

Application filed June 26, 1916. Serial No. 106,063. Term of patent 3½ years.

To all whom it may concern:

Be it known that I, THEODORE A. MOOLTEN, a citizen of the United States, and resident of the borough of Manhattan, city, county, and State of New York, have invented a new, original, and ornamental Design for Spats, of which the following is a specification.

Reference is to be had to the accompanying drawings in which Figure 1 is a side ele-

vation of a spat embodying my new design; Fig. 2 is a front elevation thereof and Fig. 3 is a plan view.

It is to be understood that my claim includes all substantial equivalents of my design as shown.

I claim —

The ornamental design for a spat as shown.

THEODORE A. MOOLTEN.
